HEATER AND BROODER STOVE

George M. Hughes, Webb, Iowa

Application October 20, 1933, Serial No. 694,436

14 Claims. (Cl. 236—6)

The object of my invention is to provide a heater and brooder stove which is simple, durable and comparatively inexpensive to manufacture.

5 A further object of my invention is to provide an air tight combustion chamber having no grate in it like ordinary heater or brooder stoves, and having only an air inlet opening and a chimney outlet so that the stove can be utilized for burning wood (a commodity always found on farms), a draft lid being provided for the air inlet opening and thermostatically controlled so as to avoid overheating of the brooder house in which the stove may be mounted and economize on the use 10 of fuel to such an extent that under ordinary conditions and average winter temperatures, the stove need not be tended or refueled but once a day.

20 A further object is to provide a draft lid hinged along its lower edge so that the lower edge of the air inlet opening is always closed to avoid any possibility of red-hot coals falling from the air inlet opening.

25 A further object is to provide a novel thermostat arrangement consisting of a supporting bar and a draft lid bar adjustably associated with each other and having a thermostat interposed between them for automatically controlling the operation of the stove dependent upon temperature conditions in the brooder house.

30 A further object is to provide an arrangement for the draft lid which will permit it to be closed by excessive air currents independent of the thermostatic control therefor.

35 Another object is to provide a brooder stove in which the combustion chamber has a peripheral bead on which a hover can rest.

40 With these and other objects in view my invention consists in the construction, arrangement and combination of the various parts of my invention, whereby the objects contemplated are attained, as hereinafter more fully set forth, pointed out in my claims, and illustrated in the accompanying drawing, in which:—

45 Figure 1 is a plan view of a brooder stove embodying my invention.

Figure 2 is a side elevation thereof showing the stove partly in section.

50 Figure 3 is a front elevation on the section line 3—3 of Figure 2.

Figure 4 is an enlarged detailed sectional view on the line 4—4 of Figure 2;

55 Figure 5 is a diagrammatic view of my stove inside a brooder house; and

Figure 6 is a plan section of a modified shape of the invention.

In the accompanying drawing, I have used the reference numeral 10 to indicate generally a brooder house. The floor thereof is indicated at 12. My stove is indicated generally by the reference character A.

The stove A comprises a sheet metal drum-like combustion chamber 14 supported by legs 16 which are secured to the bottom thereof and extend downwardly and outwardly so as to provide a substantial supporting base for the stove to prevent any tipping over thereof. A chimney 18 extends from the top of the stove and is adapted to extend through the roof 20 of the 70 brooder house 10, as shown in Figure 5.

The stove A has a fuel inlet opening 22 adapted to be covered by a cover 24 which snugly fits thereon to make the combustion chamber air tight. An inlet tube 26 provides an air inlet whereby air and its necessary oxygen enter the stove. A draft lid 28 is hinged to the inlet tube 26.

It will be noted that the hinge connection indicated at 30 is at the lower edge of the draft lid. This prevents any red-hot coals tumbling from the burning fuel within from dropping out on the floor 12 and causing a fire.

To automatically regulate the draft lid 28 I provide thermostatic means which will now be described. A supporting bar 32 is secured as by rivets or the like 34 to the bottom of the combustion chamber 14 and extends outwardly therefrom. Supported by an adjustable bolt 36 extending loosely through the supporting bar 32 90 is a draft lid bar 38. The bolt 36 extends loosely through the draft lid bar also and is provided with a wing nut 40 for adjusting purposes.

Associated with the adjusting bolt 36 is an extension 42 on the bar 38 which extends past the edge of the supporting bar 32 and is provided with indicating characters for degrees of temperature for instance.

Interposed between the bars 32 and 38 is a thermostat 44. It may be of the ordinary wafer or bellows type which are usually charged with ether for temperatures ranging from sixty to a hundred degrees. Its ends are provided with pins which fit into depressions in the bars 32 and 38.

A guide pin 46 is provided for the inner end of the draft lid bar 38. It is secured to the bar 32 as by a lock nut 48 and extends loosely through an enlarged opening 50 of the draft bar 38 (see Figure 4).

The draft lid 28 is provided with an operating arm 52 to which is pivoted an operating rod 54. The rod 54 extends loosely through an opening 56 in the supporting bar 32 whereby it is guided 5 and its lower end engages the draft lid bar 38.

The combustion chamber 14 may be provided with a pair of reinforcing peripheral beads 58 and 59. A truncated cone shaped hover 60 may rest on the upper bead 59 as shown for instance 10 in Figure 5. It will be noted that the hover 60 is comparatively deep and thus prevents the space thereunder from getting excessively hot, although it becomes warmed to the proper temperature, as accurately controlled by the thermostatic element 44. By resting on the bead 59 the hover is conveniently and simply supported 15 with respect to the stove.

In operation it will be obvious that an increase 20 of temperature surrounding the thermostat 44 will cause the same to expand and separate the outer ends of the bars 32 and 38 with the bolt 36 acting as a pivot. This will raise the inner end of the draft lid bar 38 so that the operating rod 54 will also be raised and the draft lid 28 will be swung toward closed position. This will 25 check the rate of burning of fuel in the combustion chamber 14 until the air surrounding the thermostat 44 cools enough to contract it and permit the inner end of the draft lid bar 38 to lower, whereupon the draft lid 28 will be moved 30 in an opening direction, its weight and the weight of the operating rod 54 keeping the lower end of the rod in contact with the draft lid bar 38.

It will be obvious that the draft lid 28 can be 35 closed independent of the thermostat 44. This is desirable so that when an excessive air pressure develops in the brooder house, such as might happen on a windy day, the lid 28 will be pulled closed by the excessive draft until the air pressure has subsided sufficiently to permit the draft lid to reopen and be controlled by the thermostat.

I have found that a brooder stove of this character is quite economical and efficient. It holds 40 the temperature within the brooder house at a constant degree and is very reliable in its operation.

Without the hover, the stove is also adaptable 45 for heating houses and will accurately regulate the temperature of the air in the room.

In Figure 6 I have shown the combustion chamber of oval shape rather than round and the inlet tube 26 as being round instead of square. The draft cap 28 is shown as a segment of a 50 sphere or can be cone shaped. The shape of the stove as shown in Figure 6 is, in most instances, preferable to the shape shown in the preceding figures.

Changes in the shape, as just suggested, or other changes may be made in the construction and arrangement of the parts of my device without departing from the real spirit and purpose of my invention, and it is my intention to cover 55 by my claims, any modified forms of structure or use of mechanical equivalents, which may be reasonably included within their scope.

I claim as my invention—

1. In a brooder stove, an air tight combustion chamber, a chimney rising therefrom, an air inlet opening adjacent the bottom thereof, a draft lid on said air inlet opening, a supporting bar secured to the bottom of said combustion chamber and extending outwardly therefrom, a draft lid bar below said supporting bar and pivoted inter-

mediate its ends thereto, a thermostat interposed between the outer ends of said supporting and draft lid bars, a guide pin secured to said supporting bar and extending loosely through said draft lid bar and an operating rod connected with said draft lid and engaging said draft lid bar.

2. In a brooder stove, an air tight combustion chamber, a chimney rising therefrom, an air inlet opening adjacent the bottom thereof, a draft lid on said air inlet opening, said draft lid being hinged at its lower edge thereto, a supporting bar secured to the bottom of said combustion chamber and extending outwardly therefrom, a draft lid bar below said supporting bar and pivoted intermediate its ends thereto, a thermostat interposed between the outer ends of said supporting and draft lid bars, a guide pin secured to said supporting bar and extending loosely through said draft lid bar and an operating rod connected with said draft lid and engaging said draft lid bar.

3. In a brooder stove, an air tight combustion chamber, a chimney rising therefrom, an air inlet opening adjacent the bottom thereof, a draft lid on said air inlet opening, a supporting bar secured to said combustion chamber and extending outwardly therefrom, a draft lid bar below said supporting bar and pivoted intermediate its ends thereto, a thermostat interposed between the outer ends of said supporting and draft lid bars, a guide pin secured to said supporting bar and extending loosely through said draft lid bar and an operating rod connected with said draft lid and engaging said draft lid bar.

4. In a brooder stove, an air tight combustion chamber, a chimney rising therefrom, an air inlet opening adjacent the bottom thereof, a draft lid on said air inlet opening, a supporting bar secured to the bottom of said combustion chamber and extending outwardly therefrom, a draft lid bar below said supporting bar and pivoted intermediate its ends thereto, means for adjusting said pivotal connection, a thermostat interposed between the outer ends of said supporting and draft lid bars, a guide pin secured to said supporting bar and extending loosely through said draft lid bar and an operating rod connected with said draft lid and engaging said draft lid bar.

5. In a brooder stove, an air tight combustion chamber, a chimney rising therefrom, an air inlet opening adjacent the bottom thereof, a draft lid on said air inlet opening, a supporting bar secured to the bottom of said combustion chamber and extending outwardly therefrom, a draft lid bar below said supporting bar and pivoted intermediate its ends thereto, means for adjusting said pivotal connection, means for indicating the temperature to which the thermostat is adjusted, said means comprising an extension from the side of one of said bars and extending across the edge of the other bar, a thermostat interposed between the outer ends of said supporting and draft lid bars, a guide pin secured to one of said bars and extending loosely through the other one and an operating rod connected with said draft lid, extending loosely through said supporting bar and engaging said draft lid bar.

6. In a brooder stove, an air tight combustion chamber, a chimney rising therefrom, an air inlet opening adjacent the bottom thereof, a draft lid on said air inlet opening, a supporting bar secured to the bottom of said combustion chamber and extending outwardly therefrom, a draft lid bar below said supporting bar and pivoted intermediate its ends thereto, a thermostat interposed be-

- 5 t'ween the outer ends of said supporting and draft
lid bars, and an operating rod connected with said
draft lid and engaging said draft lid bar, the
engagement connection permitting said draft lid
to be closed by air pressure independent of the
thermostat.

7. In a brooder stove, an air tight combustion
chamber, a chimney rising therefrom, an air inlet
opening adjacent the bottom thereof, a draft lid
10 on said air inlet opening, said draft lid being
hinged at its lower edge thereto, a supporting bar
secured to the bottom of said combustion cham-
ber and extending outwardly therefrom, a draft
lid bar below said supporting bar and pivoted in-
15 termediate its ends thereto, a thermostat inter-
posed between the outer ends of said supporting
and draft lid bars, and an operating rod connected
with said draft lid and engaging said draft lid
bar, the engagement connection permitting said
20 draft lid to be closed by air pressure independent
of the thermostat.

8. In a brooder stove, an air tight combustion
chamber, a chimney rising therefrom, an air inlet
25 opening adjacent the bottom thereof, a draft lid
on said air inlet opening, a supporting bar secured
to the bottom of said combustion chamber and
extending outwardly therefrom, a draft lid bar
below said supporting bar and pivoted intermedia-
30 te its ends thereto, means for adjusting said
pivotal connection, a thermostat interposed be-
tween the outer ends of said supporting and draft
lid bars, and an operating rod connected with said
draft lid extending loosely through said support-
35 ing bar and engaging said draft lid bar, the en-
gagement connection permitting said draft lid to
be closed by air pressure independent of the
thermostat.

9. In a brooder stove, an air tight combustion
40 chamber, a chimney rising therefrom, an air inlet
opening adjacent the bottom thereof, a draft lid
on said air inlet opening, a supporting bar secured
to the bottom of said combustion chamber and
extending outwardly therefrom, a draft lid bar
45 below said supporting bar and pivoted intermedia-
te its ends thereto, means for adjusting said
pivotal connection, means for indicating the tem-
perature to which the thermostat is adjusted, said
means comprising an extension from the side of
50 said draft lid bar extending across the edge of
said supporting bar, a thermostat interposed be-
tween the outer ends of said supporting and draft
lid bars, and an operating rod connected with said
draft lid and engaging said draft lid bar, the en-
55 gagement connection permitting said draft lid
to be closed by air pressure independent of the
thermostat.

10. In a brooder stove, an air tight combustion
chamber, a peripheral bead around said combus-
60 tion chamber, a hover surrounding the combus-
tion chamber and supported on said bead, a chim-
ney rising from said combustion chamber, an

air inlet opening adjacent the bottom thereof, a
draft lid on said air inlet opening, a supporting bar
secured to the bottom of said combustion cham-
ber and extending outwardly therefrom, a draft
lid bar below said supporting bar and pivoted in-
65 termediate its ends thereto, a thermostat inter-
posed between the outer ends of said supporting
and draft lid bars, and an operating rod connected
with said draft lid and engaging said draft lid bar.

11. In a brooder stove, an air tight combustion
chamber, supporting legs secured to the bottom
70 thereof and extending downwardly and outwardly
therefrom, a chimney rising therefrom, an air in-
let opening adjacent the bottom thereof, a draft
lid on said air inlet opening, a supporting bar
secured to said combustion chamber and extend-
75 ing outwardly therefrom, a draft lid bar below
said supporting bar and pivoted intermediate its
ends thereto, a thermostat interposed between
the outer ends of said supporting and draft lid
bars, and an operating rod connected with said
80 draft lid and engaging said draft lid bar.

12. In a brooder stove, an air tight combustion
chamber, a chimney rising therefrom, an air inlet
85 opening adjacent the bottom thereof, a draft lid
on said air inlet opening, an arm on said draft
lid, a supporting bar secured to the bottom of said
combustion chamber and extending outwardly
therefrom, a draft lid bar below said supporting
90 bar and pivoted intermediate its ends thereto, a
thermostat interposed between the outer ends of
said supporting and draft lid bars, and an oper-
ating rod connected with said arm on said draft
lid and with said draft lid bar.

13. In a brooder stove, an air tight combustion
95 chamber, a chimney rising therefrom, an air inlet
opening adjacent the bottom thereof, a draft lid
100 on said air inlet opening, a removable cover on
said combustion chamber, a supporting bar se-
cured to the bottom of said combustion chamber
and extending outwardly therefrom, a draft lid
bar below said supporting bar and pivoted inter-
105 mediate its ends thereto, a thermostat interposed
between the outer ends of said supporting and
draft lid bars, and an operating rod connected
with said draft lid and engaging said draft lid bar.

14. In a brooder stove, an air tight combustion
110 chamber, a chimney rising therefrom, an air inlet
opening adjacent the bottom thereof, a draft lid
115 on said air inlet opening, hinged at its lower edge
to the combustion chamber, a removable cover on
said combustion chamber, a supporting bar se-
cured to the bottom of said combustion cham-
ber and extending outwardly therefrom, a draft
120 lid bar below said supporting bar and pivoted in-
termediate its ends thereto, a thermostat inter-
posed between the outer ends of said supporting
and draft lid bars, and an operating rod connected
with said draft lid and engaging said draft lid bar.

13. GEORGE M. HUGHES.
